Primary Examiner—Ruth McInroy*(74) Attorney, Agent, or Firm*—Taylor & Aust, P.C.(57) **CLAIM**

The ornamental design for a combined barbecue shelves and console, as shown and described.

DESCRIPTION

FIG. 1 is a perspective view of a combined barbecue shelves and console showing my new design;

FIG. 2 is a top view thereof;

FIG. 3 is a front view thereof;

FIG. 4 is a side view thereof, the opposite side being a mirror image; and,

FIG. 5 is a perspective view thereof, in use with a barbecue. The details shown in broken lines in the drawings form no part of the claimed design.
